Primary Examiner — Philip S Hyder(74) *Attorney, Agent, or Firm* — Jeffrey S Melcher; Melcher Patent Law PLLC(57) **CLAIM**

The ornamental design for a cutting tool as shown and described.

DESCRIPTION

1. Cutting tool
- 1.1 : Perspective
- 1.2 : Left
- 1.3 : Left
- 1.4 : Left
- 1.5 : Right
- 1.6 : Top
- 1.7 : Front
- 1.8 : Back
- 1.9 : Bottom

The present invention relates to a handheld cutting device; In accident situations with a suspected injury, it could be very important to liberate a victim of the accident from his clothes; Figs. 1.2, 1.3 and 1.4 show different positions of a pointing element rotating with the cutting element.
